UNITED STATES PATENT OFFICE

DANIEL H. SHARTLE, OF MIDDLETOWN, OHIO

BEATER ROLL

Application filed November 19, 1928. Serial No. 320,365.

This invention relates to a beater roll and is designed more particularly for use as a part of a beater engine of the type commonly employed in the preparation of paper pulp and the like. Such beater rolls usually comprise a plurality of supporting members rotatable about a common axis and having secured about the peripheral edges thereof a series of bars, usually called fly bars, which cooperate with a fixed bed plate. The roll and bed plate are mounted in a tank in which the pulp stock, or material from which the pulp is to be formed, is floated in water, the arrangement being such that the liquid and stock will circulate through the tank and between the beater roll and the bed plate where the stock will be comminuted. With this type of beater roll difficulty has been experienced in properly securing the fly bars to the supporting members. One method of accomplishing this has been to provide the several fly bars with lugs or parts projecting beyond the respective supporting members at the ends of the roll and to shrink a metal ring about these projecting parts. This method of mounting the bars is objectionable for several reasons. For example, it is difficult to assemble the bars about the supporting members and retain the same in their proper positions prior to and during the shrinking of the ring thereon. Further, if the ring breaks all the bars are released.

One object of the present invention is to provide a device of this character having means whereby the fly bars may be quickly and easily attached thereto.

A further object of the invention is to provide such a device in which the fly bars may be mounted thereon either individually or in pairs, thus avoiding the necessity of assembling all the fly bars about the supporting members before any of the fly bars are fastened, and also permitting the removal of a single bar or a pair of bars without the necessity of removing any other bar.

A further object of the invention is to provide such a device which will be of a simple durable construction and may be produced at a relatively low cost.

Other objects of the invention will appear as the device is described in detail.

In the accompanying drawings Fig. 1 is an end elevation of a portion of a beater roll embodying my invention, showing the bed plate in section; Fig. 2 is a perspective view of a portion of such a beater roll; Fig. 3 is a transverse section taken through one pair of fly bars and the attaching bar therefor; Fig. 4 is a detail view of a portion of one of the fly bars and Fig. 5 is an elevation of the beater roll, on a smaller scale.

In these drawings I have illustrated one embodiment of my invention and have shown the same as embodied in the roll or drum of a beating engine. It will be understood that this particular construction has been chosen for the purposes of illustration only and that the invention may take various forms and may be used in connection with machines of various kinds.

In the particular embodiment here illustrated the beater roll comprises a plurality of supporting members or spiders, these supporting members being here shown in the form of disks 1 rigidly mounted on a shaft 2 which may be mounted and rotated in any suitable manner. In that form here shown the beater roll has but two supporting members, these being arranged at the respective ends of the roll. Rigidly secured to the two supporting members or disks 1 and extending lengthwise of the beater roll are a series of attaching members or bars 3 which are spaced one from the other and the outer portions of which project beyond the peripheries of the supporting members. These attaching bars may be secured to the supporting members in any suitable manner but, in the present instance, each supporting member is provided in its periphery with a series of recesses 4, in which the attaching bars are seated. Preferably the recesses are dove tailed, that is, have their lateral walls converging outwardly, and the attaching bars also have their lateral surfaces converging outwardly and are of such a size that they will fit snugly within the dove tailed slots 4. In the construction here shown, the attaching bars are inserted in the slots with a driving fit.

and no other fastening means are necessary.

Mounted on the respective attaching bars are fly bars 5 which may be secured thereto in any suitable manner and which usually 5 extend for the full length of the beater roll. In the present instance, the fly bars are arranged in pairs, the two fly bars of each pair being secured to the same attaching bar. Preferably the fly bars of each pair, which 10 are arranged on opposite sides of the attaching bar, are rigidly secured thereto by means of a pin 6 which is driven through openings 7 in the fly bars and an opening 8 in the attaching bar, and the inner edges of 15 the fly bars may rest upon the peripheral surfaces of the supporting members, thereby relieving the pins of a substantial portion of the stresses to which they would be otherwise subjected. The fly bars have the inner 20 portions of those surfaces adjacent to the attaching bars inclined to conform to the inclination of the corresponding surfaces of the attaching bar and have their outer surfaces flat, so that when secured to the attaching bar each fly bar will extend substantially radially with relation to the beater roll.

The attaching bars are so arranged that adjacent pairs of fly bars will be spaced one 30 from the other, and arranged between the adjacent fly bars of adjacent pairs of fly bars are filler strips 9 which serve to close the spaces between the fly bars and to brace the latter one against the other. Preferably 35 these filler strips are of wood and are fitted snugly into the spaces between the adjacent fly bars while dry and when immersed in the liquid in the tank of the beater engine they will swell so as to exert lateral pressure on 40 the fly bars and press the same snugly against the attaching bars, this swelling also being sufficient to retain the filler strips in position, although other fastening means may be provided if desired.

45 While I have shown and described one embodiment of my invention I wish it to be understood that I do not desire to be limited to the details thereof as various modifications may occur to a person skilled in the art.

50 Having now fully described my invention, what I claim as new and desire to secure by Letters Patent, is:

55 1. A beater roll comprising a plurality of supporting members mounted for rotation about a common axis, each of said supporting members having a circumferential series of peripheral slots, the lateral walls of each slot converging outwardly and the corresponding slots in the several supporting members being in alinement, attaching bars 60 mounted in the corresponding slots of said supporting members with a driving fit and having parts projecting beyond the peripheries of said supporting members, a fly bar arranged on each side of each attaching bar,

and means for rigidly securing said fly bars to said attaching bars.

2. A beater roll comprising a plurality of supporting members mounted for rotation about a common axis, each of said supporting members having a circumferential series of peripheral slots, the lateral walls of each slot converging outwardly and the corresponding slots in the several supporting members being in alinement, attaching bars 75 mounted in the corresponding slots of said supporting members with a driving fit and having parts projecting beyond the peripheries of said supporting members, a fly bar arranged on each side of each attaching bar, 80 each attaching bar and its associated fly bars having alined openings, and a pin driven through said openings to secure said fly bars to said attaching bar.

3. A beater roll comprising a plurality of supporting members mounted for rotation about a common axis, each having a circumferential series of peripheral slots, the walls of each slot converging outwardly and the corresponding slots in the several supporting members being in alinement, attaching bars 85 having outwardly converging lateral surfaces and fitted in the corresponding slots of said supporting members, fly bars arranged on the respective sides of each attaching bar 90 and having those surfaces which are adjacent to said attaching bar inclined to correspond to the shape of the attaching bar, means for securing said fly bars to said attaching bar, 95 and filler strips arranged between the adjacent fly bars.

4. In a device of the character described, a rotatable supporting member having a circumferential series of spaced slots, attaching members mounted in the respective slots, individually secured to said supporting member and projecting beyond the periphery thereof, and fly bars detachably secured to the projecting portions of the respective attaching members and projecting beyond the outer edges thereof.

5. A beater roll comprising a rotatable supporting structure having a circumferential series of axially extending slots, attaching bars separately secured in the respective slots and projecting beyond the periphery of said supporting structure, and fly bars rigidly secured to the respective attaching bars and having their inner edges in engagement with the periphery of said supporting structure.

6. In a beater roll, a rotatable supporting structure having a circumferential series of axially extending slots, attaching bars separately secured in the respective slots and projecting beyond the periphery of said supporting structure, and fly bars arranged on opposite sides of the projecting portion of each attaching bar and rigidly secured thereto.

7. In a beater roll, a rotatably supporting

structure having a circumferential series of axially extending slots, attaching bars mounted in the respective slots, individually secured to said supporting structure and projecting beyond the periphery thereof, and a fly bar arranged alongside of the projecting portion of each attaching bar with its inner edge adjacent to the periphery of said supporting structure and its outer edge beyond the outer edge of said attaching bar, and means for detachably securing said fly bars to the respective attaching bars.

8. A beater roll comprising a plurality of supporting members mounted for rotation about a common axis, each of said supporting members having a circumferential series of peripheral slots, the lateral walls of each slot converging outwardly and the corresponding slots in the several supporting members being in alinement, attaching bars mounted in the corresponding slots of said supporting members with a driving fit and having parts projecting beyond the peripheries of said supporting members, and fly bars arranged beyond the peripheries of said supporting members and secured to the respective attaching bars.

9. A beater roll comprising a plurality of supporting members mounted for rotation about a common axis and having alined slots, attaching bars rigidly mounted in said slots, projecting beyond the peripheries of said supporting members and spaced apart about said peripheries, fly bars secured to the respective attaching bars and arranged on adjacent sides thereof with their inner edges in contact with the peripheries of said supporting members, and a filler strip arranged between the adjacent surfaces of said fly bars.

10. A beater roll comprising a plurality of supporting members mounted for rotation about a common axis and having alined slots, attaching bars rigidly mounted in said slots, projecting beyond the peripheries of said supporting members and spaced apart about said peripheries, fly bars secured to the respective attaching bars and arranged on adjacent sides thereof with their inner edges in contact with the peripheries of said supporting members, and a filler strip of wood fitted between the adjacent surfaces of said fly bars while said filler strip is dry.

11. A beater roll comprising a plurality of supporting members mounted for rotation about a common axis, each having a circumferential series of peripheral slots, the walls of each slot converging outwardly and the corresponding slots in the several supporting members being in alinement, attaching bars having outwardly converging lateral surfaces fitted in the corresponding slots in said supporting members and projecting beyond the peripheries of said supporting members, a fly bar arranged alongside of the

outer portion of each of said attaching bars and having that surface which is adjacent to said attaching bar inclined to correspond with the shape of the attaching bar, and means for securing said fly bar to said attaching bar.

In testimony whereof, I affix my signature hereto.

DANIEL H. SHARTLE.
